VENDING CABINET

Claude H. Minturn, Pasadena, Calif.

Application April 2, 1934, Serial No. 718,642

8 Claims. (Cl. 221—104)

This invention relates to improvements in vending cabinets.

The general object of the invention is to provide an improved vending cabinet and display device wherein the articles to be vended can be kept in good condition, and where they may be readily dispensed as desired.

Another object of the invention is to provide a novel means for discharging desired quantities of merchandise from a display cabinet.

A further object of the invention is to provide a novel dispensing cabinet.

Another object of the invention is to provide a novel combined dispensing cabinet and measuring device.

Other objects and the advantages of the invention will be apparent from the following description taken in connection with the accompanying drawings wherein:

20. Fig. 1 is a side elevation embodying the features of my invention;

Fig. 2 is a fragmentary front view of my device;

Fig. 3 is a section taken on line 3—3 of Fig. 1;

Fig. 4 is a section taken on line 4—4 of Fig. 3;

25. Fig. 5 is a view similar to Fig. 4 but showing only parts of the device, and showing these parts in certain position;

Fig. 6 is a section showing the details of the catch mechanism;

30. Fig. 7 is a section partly in elevation showing details of another catch mechanism;

Fig. 8 is a section partly in elevation showing details of the measuring device; and,

Fig. 9 is a section taken on line 9—9 of Fig. 4.

35. Referring to the drawings by reference characters I have indicated my improved vending cabinet generally at 10. As shown the device 10 includes a cabinet 12 which comprises side walls 12, a bottom member 14, a front wall 15 and a rear wall 16. The front wall 15 has an aperture 17 therein which is closed by a glass panel 18 which may be mounted in any suitable manner.

Positioned in the cabinet adjacent the front wall I provide a display case 19 in which articles similar to those to be vended by the device are positioned. The display cabinet 19 is a closed box-like structure having one wall thereof made of glass as at 20 and having a removable top 20'. The display cabinet 19 is positioned in the cabinet 12 with the glass 20 thereof adjacent the glass 18 of the cabinet 12.

For closing the top of the cabinet 12 I provide a removable cover member 21 having a central circular aperture 22 therein. As shown the cover 21 overlays the upper edges of the side walls 13,

the front wall 15 and the rear wall. On the underside of the cover adjacent the edges thereof I provide a downwardly depending rail member 23 which fits against the walls of the cabinet to prevent the cover from shifting. Surrounding the aperture 22 on the upper face of the cover I provide a rail member 24, the inner face of which is spaced from the edge of the aperture 22 to provide a supporting shoulder 26.

Mounted on the cover 21 I provide a cylindrical container 27 in which is adapted to contain the articles to be vended. As shown the container 27 is made of glass with one end thereof open. When the container is positioned on the cover 21 the open end of the container is positioned in the annular rail member 24 and rests on the shoulder 26. Secured to the under face of the cover 21 I provide a plurality of spring fingers 28 which are adapted to engage the rear of the display cabinet 19 to prevent shifting thereof.

Positioned in the cabinet 12 I provide a vending mechanism which is indicated generally at 30. As shown the vending mechanism 30 includes a frame member 31 on which a hopper 32 is mounted. The hopper 32 includes spaced inclined side walls 33, an inclined front wall 34 and an inclined rear wall 35. The side walls 33 converge towards each other as do the front and rear walls to form a reduced discharge aperture as indicated at 36.

The lower edges of the side and front walls are 30 terminated on the same plane but the lower edge of the rear wall terminates a distance above the lower edges of the side and front walls as indicated at 37. (see Figs. 4 and 5). The material of the wall at 37 is bent rearwardly as at 38 and then downwardly as at 39, and then continues rearwardly to the rear of the cabinet to form a wall 40 the under face of which is on the same plane as the lower edges of the side and front wall. By thus forming the rear wall a recess 41 40 is provided below the lower edge 37 of the rear wall.

Intermediate the height of the hopper 32 I provide a baffle member 42 which is shown as an inverted V-shaped member and extends from the 45 front wall to the rear wall intermediate the side walls.

Positioned below the baffle member 42 I provide an agitator member 43. As shown the agitator 43 comprises a rod 44 which is rotatably positioned in a bearing member 45 provided in the rear wall 16 of the cabinet 12 and extends through a suitable aperture provided in the rear wall 35 of the hopper 32. Intermediate the front wall and rear wall of the hopper the rod 44 is 55

bent downward to form a finger portion 46 and adjacent the outer face of the cabinet wall 16 an operating handle 47 is provided on the rod 44.

Below the hopper 32 I provide a discharge drawer 48. As shown the drawer 48 comprises spaced side walls 49 which are suitably secured to a front member 50. The side walls 49 of the drawer are spaced apart approximately the same distance as the width of the discharge opening 36 of the hopper.

The drawer 48 is adapted to operate through an aperture 51 provided in the rear wall 16 of the cabinet with the front member 50 at the outside of the cabinet. The drawer 48 further includes a top member 52 adjacent the front thereof and a top member 53 adjacent the rear thereof. The upper surfaces of the drawer tops 52 and 53 are approximately on the same plane as the under surface of the hopper wall 40.

20 The material of the drawer top 52 is inclined downward to form a front end wall 54 and the material of the drawer top 53 is inclined downward to form rear end 55. The drawer walls 54 and 55 converge towards their lower ends to form 25 a discharge aperture as indicated at 56. When the drawer 48 is in a closed position as shown in Fig. 4 the lower end of the drawer wall 54 is spaced a considerable distance in the rear of the lower end 37 of the hopper wall 35 and the 30 upper end of the drawer wall 55 adjacent the lower edge of the hopper wall 35 and slightly to the rear thereof. The sides 49 of the drawer 48 adjacent the top include outwardly extending flange portions 57 which are positioned in U-shaped slide members 58 secured to the frame 31 (see Fig. 3).

On the front member 50 of the drawer I provide a handle member 59 by means of which the drawer may be slid in and out of the cabinet. Secured to the frame 31 below the drawer 48 I provide a holder plate 60 the upper surface of which fits snugly against the bottom of the drawer. The plate 60 extends from a point spaced forward of the lower end of the drawer wall 55, when the drawer is closed, to a point spaced in the rear of the lower end of the drawer wall 54 and is then bent downwardly at an angle as at 61 to form a guideway. Thus when the drawer 48 is in a closed position as shown in Fig. 1 the holder plate 60 forms a closure for the discharge aperture 56 of the drawer.

Below the holder plate 60 I provide a discharge hopper or chute member 62. As shown the discharge chute includes spaced side walls 63 connected by vertical front wall 64 and an inclined rear wall 65. The side walls 63 are spaced slightly farther apart than the width of the discharge aperture 56 of the drawer 48. The lower end of the inclined wall 65 is spaced from the front wall 64 to form a discharge aperture as indicated at 66 and the wall 65 is inclined at the same angle as the guide portion 61 of the holder plate 60. On the sides 63 of the discharge hopper I provide outwardly extending flange members 67 which are positioned in U-shaped slide members 68 secured to the frame 31. The discharge hopper is adapted to operate through an aperture 69 provided in the rear wall 16 of the cabinet. When the discharge hopper 62 is in an open position as shown in Fig. 4 the lower edge of the inclined wall 65 thereof extends out of the cabinet and when the discharge hopper is in a closed position the wall 64 thereof is approximately flush with the rear wall 16 of the cabinet.

Below the discharge hopper 62 I provide a closure plate 70 which is slidably mounted in the U-shaped slide members 71 secured to the frame 31. The closure plate 70 operates through the aperture 69 in the cabinet wall 16 and at its outer end includes a downwardly extending lip 72. When the closure plate 70 is in an extended position as shown in Fig. 4 it forms a closure for the discharge aperture 66 of the discharge hopper 62 and in a closed position as shown in Fig. 10 5 the lip 72 thereof engages the wall of the cabinet leaving the discharge aperture unobstructed.

10 Mounted on the end wall 64 of the discharge hopper 62 I provide a latch member 73 of any desired type including a spring pressed bolt 74 15 which projects downwardly below the bottom of the discharge hopper and in the closure plate 70 adjacent the lip 72 I provide an aperture 75 (see Fig. 6). When the discharge hopper 62 is in a closed position the latch bolt 74 enters the aperture 75 in the closure plate and when the discharge hopper is moved outward the closure plate 70 is moved with it. When it is desired to move the closure plate away from below the discharge aperture 66 of the discharge hopper 20 25 the latch bolt 74 is moved upward and the plate 70 moved towards the cabinet.

On the front member 50 of the discharge drawer 48 I provide a catch mechanism 76 of any desired type including a spring pressed bolt 30 77 which projects downward below the bottom of the drawer 48 (see Fig. 7). In one side of the latch casing I provide a horizontal aperture 78 which communicates with the aperture 79 in which the operating pin 80 operates. Thus when 35 the drawer 48 is moved outward the discharge hopper 62 will be moved outward by the latch bolt 77. Thereafter, by positioning the operating pin 80 of the latch 76 in the aperture 78 to retain the bolt 77 in a raised position the drawer 48 40 may be moved to a fully extended position and to a closed position without interfering with the discharge hopper 62.

The device 10 may be supported by any desired means such as by placing it on the counter of 45 a store or upon a shelf, etc., but in the accompanying drawings I have shown it on a standard 82. As shown the standard 82 includes four legs 83 which are connected by brace members 84. The upper ends of the legs 83 are secured to 50 four angle members 85 having horizontal webs 86 and vertical webs 87 (see Fig. 4). The horizontal webs 86 are positioned at the bottom of the angles and extends inwardly. The lower portion of the cabinet 12 fits within the vertical 55 webs of the angles 85 and the bottom of the cabinet rests on the horizontal webs 86. Adjacent the closure plate 70 a vertical web 87 is cut away as indicated at 88 to allow for the lip 72.

Mounted upon the rear wall 16, I show a 60 bracket 87 which supports a semi-cylindrical ring member 88. Quadrantal ring members 89 are mounted on the member 88 by pivots 90 and a clamping screw 91 serves to hold the ring member in cylindrical form. A measuring receptacle 65 92 is adapted to be removably held in place in the ring member and this receptacle is provided with a flange 93 adjacent the lower end. A closure 94 is provided in the receptacle 92 in alignment with the flange, and the closure is 70 mounted on a pintle 95 and is provided with a handle 96. A spring 97 serves to hold the closure in place. Below the closure a cylindrical collar 98 extends.

When the cabinet is to be used the hopper is 75

filled and the goods placed in the container 27 and in the display case 19.

In use the operator places a paper bag under the chute 63 and pulls out the drawer 48. The 5 amount of goods in the drawer will move along with the drawer and be discharged into the chute 63 and thus passes into the paper bag.

The device is operated with the latch bar 74 raised so that the closure plate 70 remains in its 10 inner position and with the latch bar raised so that it will not engage the chute 63. With the closure 70 in its inward position it will be non-effective to close communication through the chute.

15 When the measuring receptacle 92 is to be used the bag is placed below 98 thereof and thus equal measuring may be secured.

If desired a suitable electrically operated heat 20 element may be placed on the underside of the walls of the hopper channel and also container 25 27 may have its upper end removable if desired.

From the foregoing description it will be apparent that I have invented a novel vending cabinet which can be economically manufactured and 25 which is highly efficient in use.

Having thus described my invention, I claim:

1. In a vending cabinet, a hopper, a slidable open bottom drawer communicating with said hopper when said drawer is closed, means on said 30 drawer closing said hopper when said drawer is open, a slidable plate closing the bottom of said drawer when said drawer is closed, and an open bottom chute slidable beneath said drawer, said slidable plate closing the top of said chute when 35 the chute is in a retracted position.

2. In a vending device, a cabinet, a hopper positioned in said cabinet, a drawer slidably mounted in said cabinet and movable toward the rear of said cabinet, said drawer having an open 40 top and bottom, a holder plate mounted beneath said drawer and adapted to close said drawer bottom, a discharge chute slidably mounted beneath said drawer, said discharge chute having an open top and bottom, said discharge chute being slidably 45 from a position within the cabinet to a position extended from the cabinet, a closure plate slidably mounted and adapted to close the bottom of the discharge chute, and a measuring container beneath the bottom of the discharge chute when the latter is extended.

3. In a vending cabinet, a hopper, a slidable open bottom drawer communicating with said hopper when said drawer is closed, means closing 50 said hopper when said drawer is open, means closing the bottom of said drawer when said drawer is closed, an open bottom chute slidable beneath said drawer, said last mentioned means closing the top of said chute when the chute is in a retracted position and a closure for the bottom of said chute when the chute is extended.

4. In a vending cabinet including a storage compartment and hopper positioned below said storage compartment, a slidable drawer having an opening therethrough and communicating 60 with said hopper when said drawer is in a closed position and a plate on said drawer closing said hopper when said drawer is in an open position, a second plate mounted on said cabinet and extending along the bottom of said drawer below 65 said opening when said drawer is in a closed position, a dispensing chute movably mounted below

said drawer to move into and out of the cabinet, said chute being closed by said second mentioned plate when the chute is in the cabinet and a slideable closure for the bottom of said dispensing chute.

5. In a vending cabinet including a storage compartment and hopper positioned below said storage compartment, a slidable drawer having an opening therethrough and communicating with said hopper when said drawer is in a closed position and a plate on said drawer closing said hopper when said drawer is in an open position, a second plate mounted on said cabinet and extending along the bottom of said drawer below 10 said opening when said drawer is in a closed position, a dispensing chute slidably below said drawer, said chute being closed by said second mentioned plate when the chute is in a closed position and a catch on said drawer adapted to engage said chute.

6. In a vending cabinet including a storage compartment and hopper positioned below said storage compartment, a slidable drawer having an opening therethrough and communicating with said hopper when said drawer is in a closed position and a plate on said drawer closing said hopper when said drawer is in an open position, a second plate mounted on said cabinet and extending along the bottom of said drawer below 15 said opening when said drawer is in a closed position, a dispensing chute slidably below said drawer, said chute being closed by said second mentioned plate when the chute is in a closed position and a catch on said drawer adapted to engage said chute.

7. In a vending device, a cabinet, a display compartment above the cabinet and communicating therewith, a hopper in said cabinet, a drawer slidably mounted in said cabinet and movable toward the rear of said cabinet, said drawer having an open top and bottom, the rear wall of said hopper terminating above the top of the drawer, the other walls of said hopper terminating substantially flush with the top of the drawer, a 40 holder plate mounted beneath said drawer and adapted to close said drawer bottom, means on said drawer to close the hopper when the drawer is withdrawn, a discharge chute having an open top and bottom slidably mounted beneath said 45 drawer, a closure plate slidably mounted and adapted to close the bottom of the discharge chute, a catch on said discharge chute adapted to engage said closure plate, a latch on said drawer adapted to engage said chute, a measuring container secured to said cabinet beneath the bottom of the discharge chute when the latter is 50 open, and a dispensing closure for the measuring container.

8. In a vending device, a cabinet, a hopper positioned in said cabinet, a discharge chute slidably mounted beneath said hopper, said discharge chute having an open top and bottom and being slidable from a position within the cabinet to a position extended from the cabinet, slidable means to direct articles from the hopper to said chute, and a measuring container beneath the bottom of the discharge chute when the latter is 65 extended.

70 CLAUDE H. MINTURN.
